MOLTEN-BATH PROCESS FOR FIXING NITROGEN AND MEANS FOR EFFECTING THE SAME.

1,174,944.

Specification of Letters Patent. Patented Mar. 7, 1916.

Application filed October 19, 1914. Serial No. 867,374.

To all whom it may concern:

Be it known that I, JOHN E. BUCHER, a citizen of the United States, residing at Coventry, in the county of Kent and State of Rhode Island, have invented certain new and useful Improvements in Molten-Bath Processes for Fixing Nitrogen and Means for Effecting Same, of which the following is a specification.

10 In my Patent No. 1,091,425, granted March 24, 1914, I described with particularity a nitrogen fixing process in the effectuation of which a catalyzer, *e. g.* iron, was used in preferably solid and finely divided form. Herein care was exercised to avoid elevating the temperature of the reactive mass above the eutectic point of the carbon containing catalyzer, in order to preserve a very great catalytic surface containing 15 carbon in solution therein; the dissolved carbon being specially active and hence able to participate in a cyanogen compound forming reaction at even moderate temperatures. As the temperature of such a mass is gradually elevated to the said eutectic point, the reaction becomes increasingly vigorous; but when the finely divided catalyzer sinters or melts the requisite contact conditions are disturbed and the process becomes correspondingly more or less ineffective. I have been aware for a long time 20 that such a catalytic material as molten iron, even at temperatures above 1700° or 1800° C. would be available for use in the process, but the problem was to so handle such a material, in conjunction with other elements, as to reestablish the conditions under which cyanid formation could again occur copiously.

10 The present invention therefore relates to a process of and means for fixing nitrogen through the instrumentality of molten carbon dissolving catalytic material and has for one of its objects the conducting of the 15 operation so as to hold the gaseous reagent or reagents used, sufficiently long in contact with the molten iron or its equivalent, under the necessary reaction conditions, to obtain an abundant yield of the compound, 20 to be formed.

I have also aimed to keep the iron or its equivalent fully saturated with carbon, to the same end.

These and other objects of my invention will be hereinafter referred to and the novel 55 steps and mode of procedure involved in my process will be more particularly pointed out in the claims appended hereto.

In the accompanying drawing which forms a part hereof I have illustrated by a 60 vertical median section thereof, a suitable apparatus in and by means of which the process is preferably effectuated.

This apparatus is in many respects similar to a converter in construction, and comprises 65 a receptacle 1, of cast iron or the like, suitably lined, as at 2, and provided with twyars or small diametered openings 3, preferably in the bottom lining thereof, through which the gaseous reagent (bubbles of which have been designated 4) may be passed into the molten iron or like catalytic material 5, within the furnace.

The gaseous reagent is supplied to the twyars through a conduit 6, and an electrode 7 of graphite or the like is projected, through a conduit like opening 8 near the furnace bottom, into contact with said molten catalyzer. The electrode 7 may be suitably packed, as at 9, to prevent the escape 75 of the molten material, and has connected thereto a bus bar or lead 10 from a source of electric current, preferably of relatively low voltage (20 to 25 volts) and large amperage. The electrode 7 may also serve as a 80 tap for the molten iron or the like, if desired. Through one side of the casing 1 extends a conduit 11 for the introduction of graphite, or a like preferably ash-free carbonaceous 85 material, into the electric furnace; a screw 90 conveyer 12 serving to propel the graphite through the passage.

Upon the opposite side is shown a conduit 13 for the escape of the gaseous and 95 vaporous reaction products which are, of course, to be collected.

The furnace is provided with a cap 14 of suitable non-conductive material, such as will be hereinafter referred to in connection with the furnace lining. This cap may be 100 connected to an iron backing plate 15 and may in fact be molded thereupon. Through the cap extends an electrode supporting bar 16 of iron which may have therearound protective rings 17 of heat insulating material. 105 The lower extremity of this bar may be pro-

ected as shown by an electrode cap 18 which rests upon the interiorly threaded upper electrode 19, into which bar 16 is screwed; the cap 18 being of material similar to the lining. A packing 20 of kieselguhr or the like, may be used to seal the opening in the cap through which rod 16 projects; a supplemental cap 21 serving to keep this packing in place when the electrode is being elevated by the wire rope 22 attached to the eye at the upper end of rod 16. The rod 16 may also be weighted, as at 23 to insure the proper settling of the electrode 18 in the manner now to be described; this upper electrode also, preferably, being of graphite and hence not being particularly weighty.

Above the molten mass 5, is shown a charge 24 of graphite or other suitable carbonaceous material and when the weighted electrode 19, which is relatively quite large in cross-section as compared to that of the furnace interior, is allowed to descend, it presses firmly down upon the floating graphite lumps and particles and forces a large portion thereof deeply into the bulk of molten iron, as shown. This feature is of great importance as by reason thereof, a number of important results are attained. In the first place it keeps the iron or its equivalent practically saturated with carbon throughout the bulk thereof at all times. The presence of the small carbon masses throughout a large part of the molten catalyst causes the larger bubbles of the gaseous reagent used, to break up into very small ones and further holds the reagent in contact with the iron a sufficient length of time to enable the gases to efficiently participate in the reaction. By distributing the gas or gases throughout the liquid mass it also establishes the requisite extent of catalytic solution surface; since, of course, wherever a bubble of, for example, mixed nitrogen and sodium vapor is present in the liquid, such a surface is temporarily established all around the bubble, and the smaller and more numerous the bubbles, the greater the aggregate surface.

On account of the operating temperature being relatively high, as compared with, for example, the red heat preferably used when the catalyst is in the solid phase, the molten catalytic solution surface need not be so extensive as that required for the process when using a solid catalyst; but, nevertheless, the more extensive this surface, even when molten, the more efficient the process; hence another value of the small closely associated carbon masses in the melt.

Another advantage arising from this disposition of the carbon in an electric furnace is that the carbon above the upper or horizontal surface 1' of the molten catalyst, which carbon is of course in most intimate contact with the iron or the like, may be

used as an internal resistor in the furnace whereby to introduce heat directly in contact with the iron and so avoid the disadvantages of the exceedingly high temperature of the electric arc together with the attendant difficulties of current and heat regulation and distribution. The graphite particles are preferably between three and twenty mesh.

Before discussing the process further, the lining of the furnace should be considered since many commonly used linings are not available for use with the process. Accordingly the linings are prepared as follows: The very hard compact magnesia brick, such as is used in open hearth furnaces, is powdered in an iron mortar so that it may be passed through a twenty mesh sieve. To fifty parts of this powder I add fifty parts of alundum cement and from two to five parts of borax glass or borax. These materials may be mixed and ground in a suitable mill and the proportions may be varied quite widely. The above proportions were, however, those first used with alkali metal vapor and nitrogen and gave such good results that they were always used thereafter. The coarse magnesia brick powder makes the mixture so porous that after it has been sufficiently moistened and tamped very hard, it still is so porous that it can be heated directly in the blast flame without disintegrating. In fact it becomes like rock when heated by the electric arc. However, the effective contact established between the graphite particles themselves and between said particles and the upper electrode substantially prevents arcing, while further nearly all of the heat is generated in the resistor between the upper electrode and the molten iron. As the latter is an excellent conductor the heat travels downwardly rapidly so that the cyanogen compound forming reaction begins to occur the instant that the bubbles are formed at the tuyers. The furnace is preferably insulated, especially at the bottom; and if the temperature becomes too high at any time, the current may be shut off entirely for a few minutes.

The gaseous reagent employed is preferably a mixture of alkali metal vapor and nitrogen; these gases being preheated to at least 800 to 900° C. before being passed through the tuyers. If, for example, sodium be used, there may be an excess of this material, since this may be condensed to liquid after passing through the furnace and it may be readily separated from the cyanid formed, by decantation or distillation.

If the operation be conducted at approximately the lowest practicable temperatures with suitable linings, by the means herein-after indicated, it is possible to use soda ash.

or other suitable alkali compounds, for example, instead of sodium.

The soda ash may be introduced as liquid or vapor, or it, as well as suitable alkaline earth compounds may be blown into the reaction zone with a current of nitrogen or nitrogenous gas such as ammonia or producer gas.

10 The soda ash can also be caused to yield sodium by carrying it through a carbon resistor, designated 25; the sodium being liberated as per the equation:

15 The resistor is contained in a suitable receptacle 26, having therein an inner lining 27, similar to that designated 2; kieselguhr or powdered magnesia 28 being interposed between the inner lining and the iron shell

20 26 to protect the latter from the hot soda ash and also to conserve heat. I find that it is advisable to thus protect iron parts of the apparatus wherever said parts may be subjected to such a temperature as is required

25 to volatilize soda ash. Where, however, alkali metal is delivered, as such, in either liquid or vaporous condition to the charge, the intermediate kieselguhr or other refractory or basic lining is not absolutely necessary; but is preferably used, as shown at 28'. This loose graphite, coke, or other suitable carbonaceous secondary resistor is in contact at the bottom thereof with a graphite electrode 29 to which is connected the negative bus bar or lead 30 of this portion of the apparatus. A similar electrode 31 contacts with the top of the resistor and may extend

35 up through a cap and packing 32 as in the case of the stem 16 of electrode 19. The 40 positive bus bar 33 supplies low voltage current to electrode 31 and the resistor 25 may be thereby heated to incandescence.

A mixture of, for example, soda-ash and nitrogen may be led into the resistor 45 through conduit 34 and descends through the resistor to emerge therefrom as sodium vapor and carbon monoxide.

50 As to how completely this reaction takes place will of course depend upon the temperature of the secondary resistor 25; and it is preferable to effect it as fully as possible in order to supply the metallic vapor of, for example, sodium instead of the less vaporizable soda ash, to the molten catalyzer.

The strongly endothermic reaction (equation 1) may therefore be overcome, in the resistor rather than in the molten iron or the like, and if, as indicated, the reaction per equation 3 be sufficiently complete, the reaction in the molten iron will become exothermic because of the free metal vapor.

65 The coke, or its equivalent, for the secondary resistor may be supplied in any suitable

manner through conduit 34 and may be used, not only to liberate the metallic vapor of sodium or the like, but further to volatilize the soda ash or its equivalent if the latter be introduced in either solid or liquid form. Further, whether the soda ash, for example, be treated directly in the secondary resistor 25 or in the bath heated by the primary resistor 24, in either case, the great quantity of heat required when such a material is used is economically furnished and the production of the nitrogen compound sought is facilitated. This product is preferably, but of course not necessarily, cyanide; since if insufficient carbon be supplied to the reaction zone of the furnace proper, cyanamide will be formed. The carbon for this zone, while preferably obtained from the graphite mass which constitutes the primary electrode when the operation is conducted in the manner above described, may also be blown in with the gaseous reagent, or be otherwise added in the form of fuel oil, as by means of the nozzle 36. In any case, it is preferably ash-free as the accumulation of ash in the furnace is objectionable, since while the iron, manganese, oxygen, sulfur, phosphorous or alkali metals which may be present in, for example, coke ash, can do no particular harm, if any; nevertheless, silicon, calcium, magnesium and aluminium may cause considerable trouble if they be not converted to light nitrides or other light solid products, which may be blown out of the furnace at intervals or be otherwise disposed of.

When ash-free carbon is employed however the process may be started by means of the electric current and then, since the reaction is strongly exothermic when free alkali metal is used as the source of the base of the cyanogen compound to be formed, the operation may be continued for a long time until the lower linings have to be renewed. These linings, I may here state, can be heated strongly while still moist and so far not one lining has shown a crack or break after repeated usage; while in one of the earlier experiments a cast iron pot used in lieu of a furnace was partly melted from the outside of the stove-like refractory lining without injuring the latter which was used successfully in a subsequent run.

I have mentioned above the possibility of lowering the temperature of the bath or melt and this may be done by using a mixture of catalysts, iron of course being but one of the carbon dissolving substances available. Thus a ferro-manganese bath, especially if potassium be used in lieu of sodium, will permit of operating the process at a temperature which would not be effective when the catalyst is iron, alone, and the cyanogen base metal, sodium. and cobalt may in certain cases, be advantageously added to the bath to this same end.

Referring now to the drawing, and assuming that the molten catalytic material be iron at 1500° C., and that graphite particles have been forced deeply thereinto while still more graphite rests upon the molten iron above the liquid level 1', then when the pre-heated sodium-nitrogen vapor bubbles up through the molten catalyzer, the carbon in solution in the latter (the molecules of which are apparently in a peculiarly active condition) unites with the alkali metal and with the nitrogen to at once form cyanid synthetically according to the equation:

The cyanid distils out rapidly and there-after condenses easily.

The operation may be conducted at a higher temperature than I have indicated and in fact I have successfully produced cyanid in the manner just described by heating a suitable retort by means of the electric arc. I hence do not desire to be limited to any particular temperature but reiterate that the process is operative over a very considerable range of temperature, the lower limit being that at which no available catalyzer or catalytic mixture will be in other than the solid phase, and the upper limit being the temperature at which the reversible reaction tends to cause the dissociation of cyanid at a rate substantially equal to that at which it is formed.

In certain of the appended claims I have used the term "vapor" as a generic expression to cover both gaseous metal, such, for example, as sodium vapor, and volatilized sodium carbonate or the like. In either case it will be understood that such "vapor" is adapted to supply a metal capable of becoming the base of a cyanogen compound to be formed; and the term "cyanogen compound" is to be regarded as one of sufficient breadth to cover all compounds such as cyanids, cyanamids, or the like.

Finally I desire to point out a special advantage residing in the use of the gaseous reagent under pressure. If the column of molten catalyzer be one of fair depth, as shown, the pressure at which the incoming nitrogen, or nitrogen and metallic vapor, is delivered into the bath at preferably the bottom thereof, is considerably above that of the atmosphere. The gases are hence compressed and the number of molecules of nitrogen and, for example, sodium per unit of volume is correspondingly greater, which obviously tends to intensify the reaction.

Having thus described my invention what I claim is:

1. The process of operating an electric furnace to fix nitrogen therein which com-

prises subjecting a mass of molten carbon dissolving catalyzer contained in said furnace, to the action of free nitrogen and a vapor adapted to supply the base of a cyanogen compound to be formed in said molten catalyzer, to combine carbon dissolved in the latter directly with said nitrogen and base, while constantly renewing the carbon content of the catalyzer from carbon particles pressed down into the interior of said mass in part at least by the weight of excess carbon floating upon said catalyzer, and supplying heat to said furnace by passing an electric current of high density through said floating carbon.

2. The process of operating an electric furnace to fix nitrogen therein which comprises subjecting a mass of molten carbon dissolving catalyzer contained in said furnace, to the action of free nitrogen and a vapor adapted to supply the alkali metal base of a cyanogen compound to be formed in said molten catalyzer, to combine carbon dissolved in the latter directly with said nitrogen and alkali metal base, while constantly renewing the carbon content of the catalyzer from carbon particles pressed down into the interior of said mass in part at least by the weight of excess carbon floating upon said catalyzer, and supplying heat to said furnace by passing an electric current of high density through said floating carbon.

3. The process of operating an electric furnace to fix nitrogen therein which comprises electrically heating a carbon resistor in said furnace while said resistor is floating upon a bath of carbon dissolving catalytic material, said resistor having the carbon thereof in fragmentary condition to increase the extent of the carbon surface thereof presented to said bath, and reacting upon the carbon dissolved from said resistor by said catalytic material, with alkali metal and free nitrogen to form a cyanogen compound of said alkali metal.

4. The process of operating an electric apparatus to fix nitrogen therein which comprises electrically heating a carbon resistor in a part of said apparatus while said resistor is floating upon a molten bath of carbon dissolving catalytic material, and reacting upon the carbon dissolved from said resistor by said catalytic material, with alkali metal and free nitrogen to form a cyanogen compound of said alkali metal.

5. The process of operating an electric apparatus to fix nitrogen therein which comprises electrically heating a primary and a secondary carbon resistor and treating the secondary resistor with a compound adapted to react with the carbon thereof to liberate a metal capable of acting as the base of a cyanogen compound to be formed, subjecting a portion of the primary resistor to

the action of molten carbon dissolving catalytic material to dissolve carbon from said primary resistor, and reacting upon the dissolved carbon with free nitrogen and said liberated metal to form said cyanogen compound.

6. The process of operating an electric apparatus to fix nitrogen therein which comprises electrically heating an ash-free carbon resistor in a part of said apparatus while said resistor is floating upon a molten bath of carbon dissolving catalytic material, and reacting upon the carbon dissolved from said resistor by said catalytic material, with alkali metal and free nitrogen to form a cyanogen compound of said alkali metal.

7. The process of fixing nitrogen which comprises subjecting a column of molten carbon dissolving catalyzer to the action of mixed free nitrogen and a vapor adapted to supply the base of a cyanogen compound to be formed within the mass of said molten catalyzer, to combine carbon dissolved in the latter directly with said nitrogen and base, said nitrogen and vapor being under pressure.

8. The process of fixing nitrogen which comprises treating a compound, capable of being reacted upon with nitrogen and dissolved carbon to form a cyanid the base of which is the base of said compound and which reaction is endothermic in character, with incandescent carbonaceous material to liberate said base, and then reacting with the latter together with free nitrogen upon carbon dissolved in molten catalytic material to form said cyanid by an exothermic reaction.

9. The process of fixing nitrogen which comprises establishing an extended movable catalytic solution surface in a mass of molten carbon-containing iron, by injecting thereinto, under pressure a mixture of free nitrogen and a vapor adapted to supply the base of a cyanogen compound, and simultaneously reacting upon the molecules of carbon dissolved in said iron at said surfaces, with said nitrogen and vapor to form said cyanogen compound.

10. The process of fixing nitrogen which comprises subjecting a column of molten carbon dissolving catalyzer to the action of mixed free nitrogen and a vapor adapted to supply the base of a cyanogen compound to be formed in said molten catalyzer, to combine carbon dissolved in the latter directly with said nitrogen and base, the nitrogen and vapor being introduced into said catalyzer at or adjacent to the base of the column and being under pressure, whereby to intensify the reaction.

11. The process of fixing nitrogen which comprises subjecting a mass of carbon dissolving catalytic material while in the molten state and substantially saturated

with carbon, to contact with a vapor adapted to supply the base of a cyanogen compound to be formed, simultaneously causing nitrogen to contact with said catalytic material to directly combine the carbon dissolved therein with said metal and nitrogen to form said cyanogen compound, and substantially, simultaneously resaturating with carbon the catalytic material from which the dissolved carbon has been so removed, at a large number of points disposed deep in the interior of said mass.

12. The process of fixing nitrogen which comprises subjecting a mass of carbon dissolving catalytic material while in the molten state and substantially saturated with carbon, to contact throughout the bulk of said mass, with a vapor adapted to supply a metal capable of becoming the base of a cyanogen compound to be formed, and simultaneously causing nitrogen to contact in like manner with said catalytic material to directly combine the carbon dissolved therein with said metal and nitrogen to form said cyanogen compound.

13. The process of fixing nitrogen which consists in causing gaseous material, comprising nitrogen and a vapor adapted to act as the source of a cyanogen compound base, to bubble through a molten bath of carbon dissolving catalytic material which is substantially saturated with carbon, while pressing deep down into said bath a mass of finely divided carbon capable of breaking up the bubbles of said gaseous material into bubbles of materially smaller size whereby to increase the extent of molten metal surface in contact with said gaseous material and maintain said bubbles of gaseous material in contact with said catalytic material for an increased time.

14. The process of fixing nitrogen which comprises subjecting a mass of carbon dissolving material, while in the molten state and substantially saturated with carbon, to contact with bubbles comprising a mixture of free nitrogen and a metallic vapor the metal constituting which is capable of acting as the base of a cyanogen compound to be formed, to directly combine the carbon dissolved in said mass with said metal and nitrogen to form said cyanogen compound, and retarding the emergence of said bubbles from the molten material by means of solid material capable of supplying additional carbon to said carbon dissolving material.

15. The process of fixing nitrogen which comprises subjecting a mass of carbon dissolving material, while in the molten state and substantially saturated with carbon, to contact with bubbles comprising a mixture of free nitrogen and a metallic vapor the metal constituting which is capable of acting as the base of a cyanogen compound to be formed, to directly combine the carbon

- dissolved in said mass with said metal and nitrogen to form said cyanogen compound, and retarding the emergence of said bubbles from the molten material to prolong the contact between the reacting substances. 5
16. The process of fixing nitrogen which comprises establishing extended mobile catalytic solution surfaces in a mass of molten carbon dissolving material, at which 10 surfaces a cyanogen compound forming reaction may be effected, by injecting into said mass, under pressure, free nitrogen and a vapor adapted to supply the base of said cyanogen compound, and simultaneously reacting upon molecules of carbon dissolved in said material at said surfaces, with said nitrogen and vapor to form said cyanogen compound. 15
17. The process of fixing nitrogen which 20 comprises establishing extended mobile catalytic solution surfaces in a mass of molten carbon dissolving material, at which surfaces a cyanogen compound forming reaction may be effected, by injecting into said mass, under pressure, free nitrogen and a vapor adapted to supply the base of said cyanogen compound, simultaneously reacting upon molecules of carbon dissolved in said material at said surfaces, with said 25 nitrogen and vapor to form said cyanogen compound, and so retarding the upward passage through said mass of said nitrogen and vapor as to increase the aggregate extent of said surfaces. 30
18. The process of fixing nitrogen which 35 comprises establishing extended and constantly moving catalytic solution surfaces in a mass of molten carbon dissolving material, at which surfaces a cyanogen compound forming reaction may be effected, by injecting into said mass, under pressure, free nitrogen and alkali metal, and simultaneously reacting upon molecules of carbon dissolved in said material at said surfaces, with said nitrogen and alkali metal. 40
19. An electric nitrogen fixing furnace 45 comprising a mass of molten catalytic carbon dissolving material, a resistor adapted to supply carbon to said material and floating thereon, and means for introducing alkali metal and free nitrogen into said molten material to cause said metal and nitrogen to simultaneously react upon the carbon dissolved in said catalytic material. 50
20. An electric nitrogen fixing furnace 55 comprising a mass of molten catalytic carbon dissolving material, a resistor adapted to supply carbon to said material and in contact therewith, and means for introducing the base of a cyanogen compound to be formed and free nitrogen into said molten material to cause said base and said nitrogen to simultaneously react upon the carbon dissolved in said catalytic material. 60
21. An electric nitrogen fixing furnace 65 comprising a molten bath of carbon dissolving catalytic material, a resistor of carbon fragments, electrically conductive means for forcing a considerable part of said resistor down into said molten bath to supply carbon as well as electric current thereto, and means to supply a nitrogenous and cyanid-base supplying reagent to said bath capable of reacting upon the dissolved carbon therein to form a cyanogen compound. 70
22. An electric nitrogen fixing furnace 75 comprising a bath of molten carbon dissolving catalytic material, means to supply a gaseous nitrogenous and cyanid-base supplying reagent to said bath, and an electric resistor for said furnace adapted to heat the same and to prevent the too free escape of said reagent from said bath. 80
23. The process of obtaining fixed nitrogen which comprises effecting a cyanogen 85 compound forming reaction in which participate the carbon dissolved in and present throughout a mass of carbon dissolving material which is capable of acting catalytically in said reaction, free nitrogen and a vapor adapted to supply the base of the cyanogen compound to be formed, while introducing both said free nitrogen and vapor into said mass, electrically heating said material to a temperature sufficient to favor said reaction and to distil out the cyanogen compound formed, and collecting the so distilled cyanogen compound. 90
24. The process of obtaining fixed nitrogen which comprises effecting a cyanogen 100 compound forming reaction in which participate the carbon dissolved in and present throughout a molten mass of carbon dissolving material which is capable of acting catalytically in said reaction, free nitrogen and a vapor adapted to supply the base of the cyanogen compound to be formed, while introducing both said free nitrogen and vapor into said mass, electrically heating said material to maintain the same molten and to 105 distil out the cyanogen compound formed, and collecting the so distilled cyanogen compound. 110
25. The process of obtaining fixed nitrogen which comprises effecting a cyanogen 115 compound forming reaction in which participate the carbon dissolved in and present throughout a mass of carburized metal which is capable of acting catalytically in said reaction, free nitrogen and a vapor adapted to supply the base of the cyanogen compound to be formed, while introducing both said free nitrogen and vapor into said mass, electrically heating said metal to a 120 temperature sufficient to favor said reaction and to distil out the cyanogen compound formed, and collecting the so distilled cyanogen compound. 125
26. The process of obtaining fixed nitrogen which comprises effecting a cyanogen 130 compound forming reaction in which participate the carbon dissolved in and present throughout a mass of carburized metal which is capable of acting catalytically in said reaction, free nitrogen and a vapor adapted to supply the base of the cyanogen compound to be formed, while introducing both said free nitrogen and vapor into said mass, electrically heating said metal to a temperature sufficient to favor said reaction and to distil out the cyanogen compound formed, and collecting the so distilled cyanogen compound. 135

compound forming reaction in which participate the carbon dissolved in and present throughout a mass of carburized iron, free nitrogen and a vapor adapted to supply the 5 base of the cyanogen compound to be formed, while introducing both said free nitrogen and vapor into said mass, electrically heating the iron to a temperature sufficient to favor said reaction and to distil

out the cyanogen compound formed, and 10 collecting the so distilled cyanogen compound.

In testimony whereof I have affixed my signature, in the presence of two witnesses.
